UNITED STATES PATENT OFFICE.

WILLIAM H. THOMAS, OF STERLING, ILLINOIS, ASSIGNOR TO ROCK FALLS MANUFACTURING COMPANY, OF STERLING, ILLINOIS.

DESIGN FOR A FUNERAL-CAR.

48,428.

Specification for Design.

Patented Jan. 4, 1916.

Application filed May 21, 1915. Serial No. 29,675. Term of patent 3½ years.

To all whom it may concern:

Be it known that I, WILLIAM H. THOMAS, a citizen of the United States, residing at Sterling, in the county of Whiteside and State of Illinois, have invented a certain new, original, and ornamental Design for Funeral-Cars, of which the following is a specification, reference being had to the accompanying drawing, forming part thereof.

The figure is a side elevation of a motor-propelled funeral car embodying my invention.

The design comprises a plain body 1, at the upper edge of which is an ornamental strip 2, above which are plain glass panels 3, surmounted by ornamental glass strips 4. The windows 3 are provided with draperies 5, which partially fill the same.

6 is a door adjacent to the driver's seat, provided with an ornamental strip 7 corresponding with the strip 2 in position and design, the upper part of said door having a glass 8, surmounted by an ornamental glass strip 9, similar to the strips 4.

What I claim is:

The ornamental design for a funeral car, as herein shown and described.

In testimony whereof I affix my signature in presence of two witnesses.

WILLIAM H. THOMAS.
